UNITED STATES PATENT OFFICE

2,665,424

FOUNDATION GARMENT

Gaylord A. Barclay, St. Petersburg, Fla.

Application June 4, 1952, Serial No. 291,674

4 Claims. (Cl. 2-29)

1

My invention relates to foundation garments, for example, girdles and combinations of girdles and brassières or all-in-one garments, adapted to mold and confine portions of the figure of the wearer.

One object of the invention is to provide a novel and improved foundation garment having an outer front elastic panel and an outer rear elastic panel at each side thereof, a narrower diagonal inner elastic panel beneath each of the front outer elastic panels to provide firm control of the abdominal flesh, and narrow diagonal inner elastic panels beneath the rear outer panels to provide for firm control of hip and back flesh.

It is another object of the invention to provide such a foundation garment whereby firm control of flesh shall be obtained with a minimum amount of boning, and the garment shall afford the wearer freedom of movement and comfort through and above the waist and through the groin and lower part of the garment, especially through the thighs where flexibility is essential.

Other objects and advantages of my invention will become apparent as the course of the specification progresses.

To attain the objects and advantages of my invention I provide a foundation garment comprising a stretchable body encircling member adapted to extend from a point at or above the waistline of the wearer to a point below the buttocks, and a plurality of inner panels secured thereto and disposed to firmly control with outer panels of the body encircling member, areas of the abdomen, hips and buttocks with the top edge at or below the waistline and the bottom edge at or below the buttocks. The inner panels extend from a point at or below the waistline of the wearer to a point at or above the groin line so as to permit the wearer freedom of movement in the lower part of the garment.

I shall describe one form of my invention and point out the novel features thereof in claims. In the accompanying drawings,

Fig. 1 is a front perspective view of the garment as it appears on the wearer;

Fig. 2 is a rear perspective view of the garment as it appears on the wearer;

Fig. 3 is a horizontal sectional view on the line 3-3 of Fig. 1;

Figs. 4 and 6 are central transverse vertical sectional views on the planes of the lines 4-4 and 6-6 of Fig. 3 looking in the direction of the arrows;

Figs. 5 and 7 are sectional views on the planes of the lines 5-5 and 7-7, respectively, of Fig. 3.

Referring to the drawings, the garment in its preferred form includes a front section having a centrally located longitudinal front panel 1, a pair of other front panels 2 and 3 located on opposite sides of panel 1, a back section having

2

a centrally located longitudinal rear panel 4 and a pair of other rear panels 5 and 6 located on opposite sides of panel 4, and a pair of side sections comprising the respective panels 7 and 8. 5 The several panels are stitched together along vertically extending areas 9, 10, 11, 12, 13, 14, 15 and 16 to form a permanently connected tubular body encircling member which extends from the upper edge of the garment 17 to its lower edge 18.

The aforesaid front side and rear panels are of such a length that the tubular encircling member formed thereby extends from a point at or above the waistline of the wearer to a point below the buttocks. The tubular member is suitably shaped to correspond substantially with the contour of the figure. Thus its circumferential dimension at upper edge 17 is smaller than at its lower edge 18 and there is a slight fullness across the hips as indicated in Fig. 1.

The panels are all formed from single strips of material with the exception of centrally located front panel 1 and centrally located rear panel 4. Centrally located front panel 1 consists of an outer layer of material 19 and an inner layer 20. Outer layer 19 extends from upper edge 17 of the garment to its lower edge 18 but inner layer 20 extends from upper edge 17 only to edge 21 intermediate extreme edges 17 and 18. Outer and inner layers 19 and 20 are stitched into the garment together along vertically extending areas 9 and 16. Centrally located rear panel 4 comprises an upper portion 22 and a lower portion 23 which portions are stitched together along oblique extending areas 24 and 25.

A slit or opening is provided in side panel 8 extending from upper edge 17 downwardly to a suitable point 26 at the hip line of the wearer. A slide fastener is preferably provided for closing the opening thus provided, interlocking and interengaging elements 27 of the fastener being carried by tapes suitably secured to the free edges of the opening. A rider 28, of well known form, is adapted to slide along the fastening elements to interengage and disengage the same.

To stiffen the upper portion of the garment and assist in maintaining it in proper position on the body, suitable boning may be provided. The front part of the garment may, for example, be provided with stays 29 and 30 along vertical extending areas 9 and 16 respectively. As shown, the rear portion of the garment is provided with stays 31, 32, 33 and 34 which are secured to the garment along vertically extending areas 11, 12, 13 and 14. It will be understood that suitable pockets to receive and retain the stays may be formed by tapes appropriately stitched to the garment at the desired points.

In the preferred embodiment of my invention, front panels 2 and 3 are formed of elastic material

capable of stretching at least transversely of the garment, that is, in a direction around the body. Rear panels 5 and 6, and upper portion 22 of rear panel 4 are formed of a similar elastic material. Side panels 7 and 8, layers 19 and 20 of front panel 1, and lower portion 23 of rear panel 4 are formed of non-elastic material such as nylon. While in the preferred embodiment of my invention the various parts of the garment are formed of elastic or non-elastic materials according to the plan just set forth, my invention is not to be construed as necessarily limited in this fashion.

The upper edge 17 of the garment is reinforced by tape 39 and the lower edge 18 is reinforced by tape 40 both preferably stitched to the garment on the inside thereof. It will be understood that various stitched areas of the garment may be reinforced by suitable lengths of tape as desired. The lower edge of the garment is provided with suitable garter attachments 41 secured thereto at appropriate points.

According to my invention the garment is provided with a plurality of reinforcing panels such as panels 42, 43, 44 and 45. These panels are secured beneath the outer or main panels 2, 3, 5 and 6 respectively, being stitched in the garment along the hereinbefore mentioned vertically extending areas 9, 10, 11, 12, 13, 14, 15 and 16. As already noted, panels 2, 3, 5 and 6 are preferably of elastic material capable of stretching in a direction around the body and it may be noted now that their inner counterparts, panels 42, 43, 44 and 45 are also preferably of an elastic material capable of stretching in a direction around the body. In this manner, double panelling, all preferably elastic, is provided for the wearer of the garment over areas of the abdomen, hips and buttock, the effect of which is to provide firm control for flesh in these areas and to hold the flesh smooth and unrippled.

Panels 42, 43, 44 and 45 extend from a point at or below the waistline of the wearer to a point at or above the groin line so as to permit the wearer freedom of movement and comfort through and above the waist, and through the groin and lower part of the garment, especially through the hips where flexibility is essential. Preferably, these panels are wider at the hip zones than at the front and rear and their edges are diagonal; and each of these inner panels could be formed of two diagonal overlapping elastic straps.

Obviously my invention is not necessarily limited to a girdle, such as shown in the accompanying drawings, but is equally applicable to all in one garments which include a girdle and brassière in combination, and bathing suits.

Although I have herein shown and described only one form of my invention, it is to be understood that various changes and modifications may be made therein within the scope of the appended claims without departing from the spirit and scope of my invention.

Having thus described my invention, what I claim is:

1. A woman's girdle comprising a body-encircling member adapted to extend from a point at or above the waistline of the wearer to a point at or below the buttocks and including a front section, a back section and two side sections each including a panel of non-elastic material, each of said front and back sections having a central longitudinal panel of non-elastic material and a panel of elastic material at each side of and con-

nected to said central longitudinal panel extending from the top edge to the bottom edge of the garment, said elastic material having a horizontal or girthwise stretch, each elastic panel including an outer piece and an inner reinforcement piece, each of said inner pieces consisting of one piece of elastic material underlying the corresponding outer piece on the inside of the girdle and being shorter from top to bottom than the outer piece of elastic material so as to extend from a point at approximately the waistline to a point at approximately the hipline of the wearer of the garment whereby said inner elastic reinforcement pieces are shaped and located to provide control of the abdomen and hips of the wearer in addition to the control afforded by said outer pieces and said non-elastic panels of the front, back and side sections.

2. A woman's girdle as defined in claim 1 wherein said inner elastic reinforcement pieces of the front section are narrower at their front edges than at their rear edges, while said inner reinforcement pieces of the back section are wider at their front edges than at their rear edges, thereby to enhance the support and control of the abdomen.

3. A woman's girdle as defined in claim 1 wherein the top and bottom edges of said inner elastic reinforcement pieces are loose and unattached to the corresponding outer elastic pieces.

4. A woman's girdle comprising a body-encircling member adapted to extend from a point at or above the waistline of the wearer to a point at or below the buttocks and including a front section, a back section and two side sections each including a panel of non-elastic material, one of said front and back sections having a central longitudinal panel of material non-elastic girthwise and a panel of elastic material at each side of and connected to said central longitudinal panel extending from the top edge to the bottom edge of the garment, said elastic material having a horizontal or girthwise stretch, each elastic panel including an outer piece and an inner reinforcement piece, each of said inner pieces consisting of one piece of elastic material underlying the corresponding outer piece on the inside of the girdle and being shorter from top to bottom than the outer piece of elastic material so as to extend from a point at approximately the waistline to a point at approximately the hipline of the wearer of the garment whereby said inner elastic reinforcement pieces are shaped and located to provide control of the abdomen and hips of the wearer in addition to the control afforded by said outer pieces and said non-elastic panels of the front, back and side sections.

GAYLORD A. BARCLEY.
